UNITED STATES PATENT OFFICE.

NAPOLEON DU BRUL, OF CINCINNATI, OHIO.

WRAPPER-CUTTER.

SPECIFICATION forming part of Letters Patent No. 599,228, dated February 15, 1898.

Application filed April 26, 1897. Serial No. 633,858. (Model.)

To all whom it may concern:

Be it known that I, NAPOLEON DU BRUL, a citizen of the United States, residing at Cincinnati, in the county of Hamilton and State 5 of Ohio, have invented certain new and useful Improvements in Wrapper-Cutters, of which the following is a specification.

combination of the usual cutting-die surrounded by a suction-chamber, a platen through which the cutting-die projects and 55 which may have perforations or notches adjacent to the cutting-die for exhaust of air, and the beveled or recessed supporting-block loosely fitting in the cutting-die.

A further feature consists in certain means 60 in connection with the supporting-block for holding it yieldingly at or about the level of the top of the cutting-die and for easily and accurately guiding it in its up-and-down movement in the cutting-die when yielding 65 to the roller or equivalent pressure device passed over the cutting-die to cut the wrapper.

In order that my invention may be fully understood, I will proceed to describe the same with reference to the accompanying 70 drawings, in which—

Figure 1 is a plan view, Fig. 2 a vertical longitudinal section, and Fig. 3 a vertical transverse section, of the portion of a wrapper-cutter to which my invention is applied. 75 Figs. 4 and 5 are modifications of the supporting-block.

1 represents a suitable support; 2, the suction-chamber; 3, the platen surmounting said suction-chamber, and 4 the cutting-die, which 80 projects through the platen. Said platen may have openings 5 for exhaust of air from beneath the leaf, and a pipe 6 connects with suction-chamber 2 to exhaust air therefrom.

7 represents the inner platen or supporting-block, which is fitted to the cutting-die so as to leave air-exhaust space 8, and this supporting-block or inner platen has its corner beveled, as shown at 9, and which bevel extends around the periphery of said supporting-block 90 or inner platen. By this means air is exhausted from beneath the leaf which comes within the cutting-die and holds the wrapper upon said supporting-block after it is cut and until it is wrapped around the bunch. As shown 95 in Figs. 4 and 5, I may substitute for this bevel edge a rabbeted edge 9^a or a concaved edge 9^b, which will serve the same purpose as the bevel.

To afford means for yieldingly supporting 100 the block 7, I provide rods 10, projecting downwardly from said block and surrounded by springs 11, and to afford an easy and accurate guide for these rods and to preserve the

30 One object of my invention is to provide an imperforate supporting-block with a depressed seat for the edges of the wrapper, the top edges of the block being beveled or rounded off, so that when the suction is applied 35 underneath the cutting-die the leaf is brought onto the depressed edges of the supporting-block from the space which is left clear around the cutting-die, and as the supporting-block gives to the springs the rollers are 40 passed over it and the leaf is cut. By having the beveled or rounded-off portion all around or sufficiently around the edges of the supporting-block the suction holds the wrapper all around onto the supporting-block and 45 enables the rolling of the bunch into the wrapper. The advantage of this construction is the practical use of an imperforate supporting-block to avoid the drying of the wrapper.

Another object of my invention is to provide 50 an improved spring-seat for the supporting-block.

One feature of my invention consists of the

space 8 around the edge of the block said rods are made to work in sleeves 12. These sleeves are provided with heads 13, which fit transversely in the slots 14 in the support 1, 5 but which may be adjusted longitudinally in said slots to afford convenience in setting up the parts and prevent binding of the rods within their guides. Said sleeves are further provided with flanges 15, which cover the 10 slots and prevent the admission of air to the suction-chamber 2. Rods 10 are provided at the bottom with nuts 16, threaded to the ends of said rods, and washers 17, and thereby adapted to adjust the vertical position of the 15 block 7.

While it may be desirable to employ a perforated outer platen 3, this is by no means essential, as the functions of the novel features of my device will be equally well served 20 when said novel features are used in connection with a tight outer platen.

The advantage of the non-perforated supporting-block is that it prevents drying out of the tobacco-leaf, which causes breaking of 25 the wrapper, and the bevel edge causes the air to be exhausted from beneath the edges of said wrapper after it is cut, so that the wrapper will be held in position by its edges until it is removed for wrapping about the 30 bunch.

Whether the supporting-block be beveled, as shown in Figs. 1, 2, and 3, or rabbeted, as shown in Fig. 4, or concaved, as shown in Fig. 5, it will be seen that in either case the 35 edge is cut away, so as to form substantially the same construction, and I do not therefore limit myself to any particular way of cutting away the edge.

Having thus described my invention, what

I claim as new therein, and desire to secure by 40 Letters Patent, is—

1. An imperforate supporting-block having its peripheral upper edge cut away to provide a depressed seat for the edges of the cut wrapper in combination with a cutting-die, separated from the supporting-block and in which the supporting-block is located, a suction-chamber, and means for exhausting the air from the suction-chamber; substantially as described. 45

2. The combination of a suitable support having slots, the guide-sleeves having heads fitting in the slots, and flanges whereby they are supported, the springs surrounding the guide-sleeves, the supporting-block seating 55 on the springs and sliding in the guide-sleeves, the cutting-die surrounding and separated from the supporting-block, a suction-chamber, and means for exhausting the air from the suction-chamber; substantially as de- 60 scribed.

3. The combination of a suitable support having slots, the guide-sleeves having heads fitting in the slots, and flanges whereby they are supported, the springs surrounding the 65 guide-sleeves, the supporting-block seating on the springs and having screw-threaded rods sliding in the guide-sleeves, the washers, the nuts for adjusting the rods in the guide-sleeves, the cutting-die surrounding 70 and separated from the supporting-block, a suction-chamber, and means for exhausting the air from the suction-chamber; substantially as described.
